United States Patent Office

Des. 211,324
Patented June 11, 1968

211,324

HANDLE

Albert S. Kirk, Broomall, Pa., assignor to Southco Incorporated, Lester, Pa., a corporation of Pennsylvania

Filed Dec. 4, 1967, Ser. No. 9,619

Term of patent 14 years

(Cl. D10—8)

Fig. 2

FIG. 1 is a plan view of the handle embodying my new design;

FIG. 2 is a section through the cup of the design shown in FIG. 1 taken as indicated by the lines and arrows II—II in FIG. 1;

FIG. 3 is a section taken as indicated by the lines and arrows III—III in FIG. 1.

The broken lines indicating the panel through which the cup is mounted, and the shaft of the handle, are shown for illustrative purposes only.

I claim:

The ornamental design for a handle, as shown and described.
